UNITED STATES PATENT OFFICE.

EDGAR ISON PARKES, OF BUSHEY, ENGLAND.

CEILING-ROSE.

1,203,650.

Specification of Letters Patent.

Patented Nov. 7, 1916.

Application filed October 26, 1911. Serial No. 656,921.

To all whom it may concern:

Be it known that I, EDGAR ISON PARKES, a subject of the King of Great Britain, residing at Waterslade, Bushey Hall Road, 5 Bushey, in the county of Herts, and formerly of Idolholme, Lancaster Road, New Barnet, in the county of Hertford England, have invented new and useful Improvements in Ceiling-Roses, of which the following is a 10 specification.

This invention relates to ceiling roses. Its purposes is to provide a sound mechanical construction of rose which shall have the advantage of convenience in use.

15 It is a particular object of the invention to produce a ceiling rose from which the terminals may be removed for attachment of the conductors, and in which no mechanical stress shall be taken by the electrical connections nor by the cover.

20 It is also a purpose of the invention to avoid altogether the use of screws passing into insulating material and generally to secure adequate insulation of the metal parts 25 of opposite polarity.

More particularly defined the invention comprises a ceiling rose having plug and 30 socket or other conveniently removable terminal blocks, slid into recesses in the insulating base, said base having also formed upon it a cord grip to take the weight of the fitting.

These and further meritorious features of 35 the invention will appear more clearly hereinafter and will be particularly delimited in the appended claims.

In the accompanying drawings which show a preferred construction of the invention;

40 Figure 1 is a plan of the ceiling rose with the cover removed, and Fig. 2 is an elevation with the cover in section.

From Fig. 1 it may be seen that the porcelain base 1 is formed with two upstanding 45 ribs 2, 3, at right angles to one another. The rib 3 serves to separate and insulate from each other the metal parts of opposite polarity. The rib 2 has two square holes through it close against either side of the 50 rib 3. Each of these receive a short metal bar or block 4 of square section. From one end of the block there extends into it a longitudinal hole 5 and at the other end is a transverse hole 6. This latter serves to 55 receive the circuit wire which is clamped in place by the screw 7. The longitudinal hole

receives a split pin 8 which may be of ordinary form. This pin has also a transverse perforation 9 in which the flexible conductor may be secured by the screw 10. 60 At the back of the base the openings 11 for the passage of the circuit wires are preferably coned as seen in Fig. 2. The ends of the rib 2 are notched on the upper surface and at the side as indicated at 12, 13, and 65 it will be noted that the ends of the rib are in close proximity to the cover 14.

The article may be used as follows. The plug 8 is withdrawn from the socket. The socket wire is put through hole 6 and 70 clamped by screw 7; the socket and the channel in the base being non-circular, the former cannot turn as the screw is tightened. The flexible conductors are then fastened in the holes 9 of the plugs 8—which obviously may 75 be done on the floor or at the workshop—and the plugs are pressed home into the sockets. Each conductor is passed over the notch 12 and around the notch 13 as indicated in Fig. 2 so that the ends of the rib 2 support the 80 weight of the fitting.

To prevent stress on the circuit wires when the plugs are pressed in, small projections 15 may be formed in the porcelain. These engage between the head of the screw 7 and 85 the block 4 as indicated, and the head of the screw is enlarged so that the block cannot be withdrawn unless the screw is first taken out.

Obviously the ceiling rose may have more 90 than two terminals according to the purpose it is to serve. They may be arranged in quite similar manner each with an insulating rib separating it from the next.

It is to be noted that as there are no 95 screws screwing into the insulating material in the rose, if the latter is of porcelain the whole may be glazed and then at no point can the metal terminals come into contact with unglazed porcelain.

100 What I claim is:

1. In a ceiling rose or like fitting, the combination of an insulating base, a cord grip integral therewith, circuit terminals slidably mounted in and supported by said base, and lamp terminals carried by and slidably mounted in said circuit terminals.

105 2. In a ceiling rose the combination of an insulating base, an insulating rib integral with said base and upstanding therefrom, terminals slidably mounted in said rib, a cord grip on said rib and a transverse

rib on said base separating the terminals of opposite polarity.

3. In a ceiling rose, the combination of an insulating base, two upstanding ribs on said base arranged to form a cross, one of said ribs having a pair of non-circular holes one on either side of the other rib, a pair of metal blocks each passing through one of said holes, means for connecting one of the main wires to each of said metal blocks, a pair of plugs one fitting into each of said metal blocks and means for connecting the flexible wires to said plugs.

4. In a ceiling rose, the combination of an insulating base, an insulated rib upstanding therefrom and pierced with a pair of non-circular holes passing therethrough, a pair of metal blocks one fitting into each of said holes, a terminal screw for a main wire at one end of each of said metal blocks, a plug terminal at the other end of each of the metal blocks adapted to take the flexible wires, and a stop integral with the insulating base with its effective surface parallel to said pierced rib and at right angles to the direction of sliding of said metal blocks and located to take the thrust of each of the metal blocks when said plugs are inserted and to prevent removal of said metal blocks without removal of said terminal screws.

5. In a ceiling rose, the combination of an insulating base, a perforated insulating rib upstanding therefrom, metal sockets passing through the perforations in said

ribs, means for securing circuit wires to said sockets, metal plugs sliding in and making electric connection with said sockets, and means for securing lamp wires to said plugs.

6. In a ceiling rose, the combination of a slotted insulating base, recessed terminal blocks for the main wires non-circular in section fitting in and freely slideable in said base, terminal screws in said blocks coaxial therewith and terminals for the lamp wires freely slideable in the terminals for the main wires.

7. In a ceiling rose the combination of an insulating base, a cord grip integral therewith, recessed circuit terminals slideably mounted in said base, lamp terminals fitting in said circuit terminals, and upstanding ribs in said base in the path of movement of said circuit terminals.

8. In a ceiling rose, the combination of an insulating base, terminal blocks slideable in said base, a rib integral with said base and adjacent to the ends of said blocks when the latter are in position, and terminal screws in said blocks but passing loosely over said rib and having heads too large to pass over said rib.

In testimony whereof I have signed my name to this specification in the presence of two subscribing witnesses.

EDGAR ISON PARKES.
